Rand Corporation, a corporation of Delaware

Application September 4, 1953, Serial No. 378,509

11 Claims. (Cl. 315—3.5)

This invention relates to a microwave oscillator, and more particularly, is concerned with a tunable travelling wave tube type oscillator.

It is the general object of this invention to provide an improved oscillator for operation in the microwave frequency region, the oscillator being characterized by its broad tuning range, frequency stability, and simple output coupling arrangement.

Another object of this invention is the provision of an oscillator utilizing interaction between an electron beam and an electromagnetic field in which the interaction region is positioned entirely within a hollow wave guide transmission line.

Another object of this invention is to provide a microwave oscillator in which the frequency of oscillation is substantially independent of variation in load impedance.

Another object of this invention is the provision of a microwave oscillator which may be either electrically or mechanically tunable, or both, depending on its mode of operation.

These and other objects of the invention which will become apparent as the description proceeds are achieved by the provision of an electron discharge apparatus including an electron gun for producing a stream of electrons, and a collector. A hollow rectangular wave guide section extends between the gun and the collector, the longitudinal axis of the wave guide being perpendicular to the electron stream with the narrow walls of the wave guide having apertures therein to permit passage of the electron stream across the interior of the wave guide section. Sealed windows are provided on either side of the electron stream region to permit evacuation in this region. An interaction structure is positioned within the wave guide along the path of the electron stream, the interaction structure including a pair of conductive members secured to the inner surfaces of the broad walls of the wave guide, the members having opposed parallel surfaces, with a plurality of conductive fins extending from these surfaces, the fins projecting towards the opposite member. The fins projecting from each member are spaced between a pair of fins projecting from the opposite member so that an interleaved structure is provided. Each of the fins has an opening therein positioned along the axis of the stream for permitting passage of the electron stream through the interaction structure. Mechanical tuning is achieved by providing mechanical adjustment of the spacing between the two parallel surfaces of the conductive members.

For a better understanding of the invention, reference should be had to the accompanying drawings, wherein:

Fig. 1 is a plan view, partially in section, of the oscillator tube;

Fig. 2 is a sectional view taken substantially on the line II—II of Fig. 1;

Fig. 3 is a perspective view of the tube of Fig. 1; and

Fig. 4 is a fragmentary cross-sectional view taken substantially on the line IV—IV of Fig. 2.

Referring to the drawings, the numeral 10 indicates

2

generally an electron gun of conventional design including a cathode 12, a heater 14, and accelerating anode 16. These electrodes are supported from a base 18 which is provided with pins 20 and suitable internal connections (not shown) by means of which heater current may be supplied to the heater 14 and a negative cathode potential may be applied between the cathode 12 and anode 16, the anode being normally at the ground potential of the envelope of the tube.

10 The electron gun 10 is secured in sealed arrangement to the narrow wall 22 of a rectangular wave guide section, indicated generally at 24, by means of an insulating glass seal 26, mounting ring 28, and mounting flange 29. An aperture 30 through the narrow wall 22 permits passage of the electron stream from the cathode 12 transversely across the center of the wave guide section 24. An aperture 31 in the opposite narrow wall 32 of the wave guide section 24 permits the electron stream from the cathode 12 to impinge on a collector, indicated generally at 33, including a collector electrode 44. The collector 33 is supported in hermetically sealed relation to the wave guide section 24 by means of a glass seal 34 and associated mounting rings 36 and 38, the ring 36 being supported by an annular mounting flange 40 secured to the narrow wall 32 of the wave guide section 24. The collector 33 is normally maintained at the ground potential of the wave guide section 24. Cooling discs 42 may be provided surrounding the collector electrode 44. Magnetic focussing of the electron stream to maintain a narrow beam may be provided by an external magnet (not shown) in conventional manner, the poles of the magnet being in the form of yokes which may be clamped around the mounting rings 28 and 40. For an example of magnetic focussing of an electron beam in similar types of high frequency tubes see pending application Serial No. 117,187 filed in the names of Rich and Wang, now U. S. Patent 2,687,490, issued August 24, 1954.

To provide an evacuated envelope for the electron stream, mica windows 46 and 47 are positioned across the ends of the wave guide section 24. The mica windows are clamped in position by adjacent wave guide sections 48 and 50 respectively, each of the wave guide sections 48, 24, and 50 being provided with flanges 52, 54, 56, 58, 60 and 62 at the respective ends thereof. Flanges 54 and 56 and flanges 58 and 60 are bolted together as by bolts 64 to secure the wave guide sections together. Suitable wax is preferably applied between the surfaces of each mica window and adjacent surfaces of the flanges to provide an airtight seal at the ends of the wave guide section 24.

50 Situated within the wave guide section 24 along the axis of the electron beam are a pair of conductive blocks 66 and 68 having opposed flat parallel surfaces 70 and 72 respectively. The block 66 is secured to the upper broad wall 74 of the wave guide section 24 and is provided with a plurality of conductive fins 76 preferably integral with the block 66, projecting from the surface 70 as to extend across the axis of the electron stream. Each of the projecting fins 76 is provided with a slotted opening 78, the slots lying along the axis of the electron stream to permit the passage through the fins 76 of the electrons as they pass from the electron gun 10 to the collector 32.

The opposing block 68 is similarly provided with a 65 plurality of projecting fins 80 which extend between the fins 76 so as to form an interleaved or inter-digital structure. The fins 80 are similarly provided with slots 82 to permit passage of the electron stream through the interleaved fins. The width of the fins 76 and 80, as measured in a direction parallel to the longitudinal axis of the wave guide, is not critical but should be the minimum required

to achieve a well defined field in the regions between the fins. The number of fins depends on the desired frequency of operation and beam voltage, as will hereinafter become apparent.

To provide mechanical tuning, the block 68 is made adjustable relative to the block 66. This adjustment is provided by means of a rectangular opening 83 in the broad wall 84 of the rectangular wave guide section 24 through which the lower end of the block 68 extends. A choke member 86 is provided on the outside of the rectangular wave guide section 24, the choke member 86 having an opening 87 registering with the opening 82 in the rectangular wave guide and being provided with annular choke slots 88 and 90.

The block 68 is adjustively supported by means of a rod 92 having a threaded member 94 secured to the end thereof opposite to the end of block 68. The member 94 includes a flange portion 96, a bellows 98 extending between the choke member 86 and the flange 96 to provide a vacuum seal. The threaded member 94 is clamped by means of locking nuts 100 and 102 to a bracket 104 rigidly supported as by being brazed or otherwise secured to the choke member 86. By loosening and adjusting the position of the locking nuts 100 and 102, the distance between the surfaces 70 and 72 of the blocks 66 and 68 can be readily adjusted.

As is hereinafter pointed out in the discussion of the operation of the tube, it is desirable that one end of the wave guide transmission line be terminated in an adjustable short circuit. This is provided by a short circuiting plunger 106. Adjustment of the plunger 106 within the wave guide 48 is provided by means of a micrometer adjustment, indicated generally at 108, having a calibrated adjusting knob 110. A key 112 engages a groove in the micrometer shaft 114 to prevent rotational movement of the plunger 106. The entire adjustable short circuit assembly is supported in position by a flange 116 bolted as by means of bolts 118 to the flange 52 on the wave guide section 48.

According to the preferred mode of operation of the oscillator as above described, the oscillator functions substantially as a backward-wave travelling wave oscillator. As in the conventional backward-wave oscillator, the electron beam in passing through the interaction structure excites an electromagnetic wave which is propagated back toward the source. The interaction structure therefore propagates electromagnetic energy, and acts as a conventional slow wave propagating structure. The frequency of this wave is a function of the electron velocity and therefore a function of the beam voltage on the anode. To get energy to transfer from the electron stream to the field, the electron velocity must be such that it moves from one fin to the next in a period of time slightly less than the period of one half cycle of the electromagnetic wave less the time it takes the wave to travel that distance. The frequency of the field will adjust itself according to the electron velocity to maintain this condition for oscillation.

In the conventional backward-wave oscillator, the interaction or slow wave propagating structure must be made quite long so that there is sufficient distributed feedback to start oscillation. In the present oscillator, the slow wave propagating structure is relatively short. However, it is terminated at the ends thereof in an open circuit which acts as a reflective termination. If the length of the slow wave propagating structure is an integral number of half wavelengths long, waves traveling in the same direction reinforce each other and are continuously acted on by the electron beam. Oscillation results with much shorter length of interaction structure because of the additional feedback introduced by the reflective terminations.

Thus oscillation is sustained where the interaction structure is resonant, namely, where the length is an integral

number of half wavelengths longs, which condition may be expressed mathematically as

$$L = \frac{1}{2} n \lambda_g \quad (1)$$

The wave length λ_g in turn may be expressed in terms of the phase velocity v_o of the fundamental and the frequency as

$$\lambda_g f = v_o \quad (2)$$

so that the frequency of oscillation, by equating (1) and (2), is

$$f = \frac{3}{4} n v_o \frac{1}{L} \quad (3)$$

This equation may be used to calculate the frequencies at which the tube will oscillate for a given phase velocity and axial length of the interaction or slow wave propagating structure. The phase velocity is substantially independent of frequency and may be determined rather closely in terms of a wave travelling at the speed of light along the serpentine path defined by the interleaved fins. Thus the phase velocity is substantially equal to the velocity of light multiplied by the ratio of the serpentine path length to the axial path length, or

$$v_o = c \times \frac{S}{L} \quad (4)$$

where S is the length of the serpentine path and c is the velocity of light.

The beam voltage, i. e., the applied potential between the cathode 12 and the anode 16, depends on the desired frequency and the spacing between the fins. The voltage to give oscillation at a given design frequency can be determined in the following manner: As pointed out above, to get oscillation, the electron should traverse the distance from one fin to the next in a time slightly less than the period of one half cycle of the electromagnetic wave less the time it takes the wave to travel that distance, or expressed mathematically

$$\frac{d}{v} = \frac{1}{2f} - \frac{d}{v_o} \quad (5)$$

where d is the center distance between adjacent fins and v is the electron velocity. Solving for electron velocity gives

$$v = \frac{2fd}{1 - \frac{2fd}{v_o}} \quad (6)$$

Since the electron velocity is related to the beam voltage v_o by the equation

$$V_o e = \frac{1}{2} m v^2 \quad (7)$$

where e is the charge and m is the mass of an electron, the value of V_o for a given frequency f and fin spacing d can be readily calculated from Equations (6) and (7). Actually the voltage should be slightly greater than this calculated figure, but oscillation has been found to take place over a 20% voltage range with the value calculated by the above equations representing the lower limit.

With the interaction structure functioning as a resonant device, the beam voltage has negligible effect on the frequency as long as the electron velocity is held within the 20% voltage spread in which interaction takes place between the electron beam and the electromagnetic field for a particular mode of oscillation. Change in voltage does affect the power output.

The mode of oscillation as represented by the integral number n in the above equations can be changed by shifting the beam voltage to a value where interaction takes place for a different wavelength at which the slow wave propagating structure is resonant. Thus, by changing the beam voltage in predetermined steps, the mode of oscillation can be changed with a corresponding jump in the frequency. It should be noted that the lowest mode of oscillation may be below the cutoff frequency of the

wave guide and therefore not obtainable. Generally, operation in the lower modes is further limited by the fact that the beam voltage becomes too low to get sufficient beam current.

Mechanical tuning within a given resonant mode of oscillation can be effected by changing the serpentine path length, as by changing the spacing between the parallel plates in the manner above described. This results in a change in the velocity of the fundamental with a resultant change in frequency. If the phase velocity is changed very much by the mechanical tuning, there must be an accompanying change in the beam voltage, however, for interaction between the beam and the field to sustain oscillation. Continuous tuning is thus possible over a reasonably wide frequency range by tuning modes mechanically and shifting modes electronically. Because the frequency is substantially independent of variations in beam voltage in a given mode of oscillation, the frequency of the output is quite stable.

Coupling of energy from the transverse propagating structure to the wave guide is provided by fringing field effects existing along the sides of the wave propagating structure. For this reason, coupling to the wave guide is light, and loading has negligible effect on the frequency of oscillation.

There is a second mode of operation by which the tube structure above described can be made to oscillate. Assume for the moment that the wave guide section is excited by a microwave signal of a certain frequency. At a given instant, then all the fins projecting from one side of the guide in the slow wave propagating structure will be at substantially the same potential with respect to the fins projecting from the opposite side of the guide. If an electron travels from fin to fin in one-half cycle of the energy propagated along the wave guide, it experiences a net electric field in one direction, since the effect of the alternating potential at the fins exactly cancels the alterations in the field. Thus the electron travels at the same speed as an apparent travelling wave. This apparent wave can be thought of as a spatial harmonic of a wave travelling with infinite phase velocity.

If a beam of electrons is sent through the interaction structure at a speed corresponding to exact synchronism with the velocity of this apparent spatial harmonic, just as many electrons are accelerated as are decelerated so that there is no net transfer of energy between the electron stream and the electromagnetic field. However, if the beam is travelling somewhat slower than the spatial harmonic wave, the beam will gain energy from the field, whereas if the beam is travelling somewhat faster than the spatial harmonic wave, the electronic stream will give up energy to the electromagnetic field. In the latter case, if the energy gained is sufficient to supply the loss in the tube and in any loads on either end of the output wave guide transmission line, the system is self-oscillatory. The frequency then is determined by the beam voltage. As the voltage is changed, the oscillation frequency changes so as to maintain the phase velocity of the apparent spatial harmonic travelling wave slightly greater than the electron velocity.

Normally the oscillator is tuned to oscillate at a frequency where the interaction structure is not resonant, since at such frequencies where the interaction structure is resonant, electronic tuning becomes ineffective and the oscillator goes into resonant oscillation. Resonant oscillation can be reduced or eliminated by providing energy absorbing non-reflective terminations at either end of the interaction structure, as by inserting attenuating material between the fins. This prevents reflection of electromagnetic waves along the interaction structure parallel to the electron stream axis, so that backward-wave oscillation can not take place.

The short circuit provided by the tuning plunger is adjusted to balance out the shunt susceptance introduced by

the interaction structure in the wave guide transmission line, so that the oscillator can be matched to the transmission line. By changing the position of the short at the same time the beam voltage is varied, a wide range of frequency may be achieved over which the oscillator can be tuned.

From the above description it will be seen that the various objects of the invention have been achieved by the provision of a unique tube structure which functions as a microwave oscillator. The interaction structure along the beam is extremely short compared to that in known travelling wave tube type oscillators, which permits mounting within a transverse wave guide transmission line. The result is a relatively compact structure having a convenient output coupling means in the transverse wave guide. Electronic or mechanical tuning is available depending on the mode of operation.

In the preferred mode of operation, namely, where the interaction structure acts as a resonant circuit, electromagnetic energy is actually propagated along the structure parallel to the electron stream and transversely of the wave guide. Thus the interaction structure operates as a conventional slow wave propagating wave guide, that is, there is a phase shift along it. However, in the alternative mode of operation there is no phase shift along the interaction structure, all the fins projecting from one side being in the same phase as determined by the fundamental wave propagated by the wave guide transmission line 24.

While tuning out the shunt susceptance of the interaction structure in the wave guide transmission line is essential in the non-resonant mode of oscillation, it is not essential that the transmission line be terminated in a short circuit at one end in the resonant mode of operation. For this reason the short circuit is shown mounted externally of the vacuum envelope of the tube, so that it may readily be detached if desired. However, it may as well be positioned within the vacuum envelope where the tube is to operate primarily in the non-resonant mode.

The mechanical tuning is of no significance in the non-resonant mode of oscillation. Adjustment of the spacing between the two blocks of the interaction structure may be eliminated therefore if desired, where operation is non-resonant or at a non-tunable resonant frequency.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Electron discharge apparatus comprising an electron gun and collector, the electron gun producing a stream of electrons directed along an axis, a hollow rectangular wave guide section having a pair of narrow walls and a pair of broad walls, the wave guide section extending between the gun and collector, the axis of the electron stream being perpendicular to the longitudinal axis of the wave guide section, each of the narrow walls of the wave guide section having an aperture therein to permit passage of the electron stream across the interior of wave guide section, and means positioned in the wave guide section transverse said longitudinal axis and along the axis of the electron stream including a pair of conductive blocks having spaced parallel surfaces and a plurality of conductive fins projecting from said surfaces, the fins projecting from one block extending between the fins projecting from the other block, whereby an interleaved structure is provided across the interior of said wave guide section, each of the fins having an opening therein, the openings being positioned along the axis of the electron stream to permit passage thereof through said means, and means for adjustably positioning at least one

of the blocks to vary the spacing between said parallel surfaces.

2. Electron discharge apparatus comprising an electron gun and collector, the electron gun producing a stream of electrons directed along an axis, a hollow rectangular wave guide section having a pair of narrow walls and a pair of broad walls, the wave guide section extending between the gun and collector, the axis of the electron stream being perpendicular to the longitudinal axis of the wave guide section, each of the narrow walls of the wave guide section having an aperture therein to permit passage of the electron stream across the interior of wave guide section, and means positioned in the wave guide section transverse said longitudinal axis and along the axis of the electron stream including a pair of conductive blocks having spaced parallel surfaces and a plurality of conductive fins projecting from said surfaces, the fins projecting from one block extending between the fins projecting from the other block, whereby an interleaved structure is provided across the interior of said wave guide section, each of the fins having an opening therein, the openings being positioned along the axis of the electron stream to permit passage thereof through said means.

3. Electron discharge apparatus comprising an electron gun and collector, the electron gun producing a stream of electrons directed along an axis, a hollow rectangular wave guide section having a pair of narrow walls and a pair of broad walls, the wave guide section extending between the gun and collector, the axis of the electron stream being perpendicular to the longitudinal axis of the wave guide section, each of the narrow walls of the wave guide section having an aperture therein to permit passage of the electron stream across the interior of wave guide section, and means positioned in the wave guide section transverse said longitudinal axis and along the axis of the electron stream including a pair of conductive blocks having spaced parallel surfaces and a plurality of conductive fins projecting from said surfaces, each of the fins having an opening therein, the openings being positioned along the axis of the electron stream to permit passage thereof through said means.

4. Electron discharge apparatus comprising an electron gun and collector, the electron gun producing a stream of electrons directed along an axis, a hollow rectangular wave guide section extending between the gun and collector, the axis of the electron stream being perpendicular to the longitudinal axis of the wave guide section, the narrow side walls of the wave guide section having apertures therein to permit passage of the electron stream across the interior of said wave guide section, and slow wave propagating means positioned in the wave guide section along the axis of the electron stream, and transverse the longitudinal axis of said wave guide section.

5. A microwave oscillator comprising a hollow wave guide transmission line having a longitudinal axis of propagation, an adjustable short circuit termination at one end of the transmission line, means for directing an electron stream transversely across the interior of the hollow wave guide transmission line along an axis perpendicular to said axis of propagation, means transparent to microwaves in the transmission line on either side of the region of the electron stream for providing an airtight seal whereby the region of the electron stream may be evacuated, and slow wave propagating means positioned within the transmission line along the axis of the electron stream transverse the longitudinal axis of propagation of said wave guide transmission line, said means including a pair of spaced conductive members on either side of the electron stream and inter-digital conductive fins projecting from said members and extending across the electron stream within the interior of said hollow wave guide transmission line, the fins having openings therein aligned along the axis of the electron stream for passage of the stream through the inter-digital fins.

6. A microwave oscillator comprising a hollow wave guide transmission line having a longitudinal axis of propagation, an adjustable short circuit termination at one end of the transmission line, means for directing an electron stream transversely across the interior of the hollow wave guide transmission line along an axis perpendicular to said axis of propagation, means transparent to microwaves in the transmission line on either side of the region of the electron stream for providing an airtight seal whereby the region of the electron stream may be evacuated, and means positioned within the transmission line along the axis of the electron stream transverse the longitudinal axis of propagation of said wave guide transmission line, said means including a pair of spaced

10 conductive members on either side of the electron stream and inter-digital conductive fins projecting from said members and extending across the electron stream within the interior of said hollow wave guide transmission line, the fins having openings therein aligned along the axis of the electron stream for passage of the stream through the inter-digital fins.

15 7. A microwave oscillator comprising a hollow wave guide transmission line having a longitudinal axis of propagation, means for directing an electron stream transversely across the interior of the hollow wave guide transmission line along an axis perpendicular to said axis of propagation, means in the transmission line on either side of the region of the electron stream for providing an airtight seal whereby the region of the electron stream may be evacuated, and means positioned within the transmission line along the axis of the electron stream transverse the longitudinal axis of propagation of said wave guide transmission line, said means including a pair of spaced

20 conductive members on either side of the electron stream and inter-digital conductive fins projecting from said members and extending across the electron stream within the interior of said hollow wave guide transmission line, the fins having openings therein aligned along the axis of the electron stream for passage of the stream

25 through the inter-digital fins.

8. A microwave oscillator comprising a hollow wave guide transmission line having a longitudinal axis of propagation, means for directing an electron stream transversely across the interior of the hollow wave guide transmission line along an axis perpendicular to said axis of propagation, and means positioned within the transmission line along the axis of the electron stream transverse said longitudinal axis of propagation of said wave guide transmission line, said means including a pair of spaced

30 conductive members on either side of the electron stream and conductive fins projecting from said members and extending across the electron stream within the interior of said hollow wave guide transmission line, the fins having openings therein aligned along the axis of the electron stream for passage of the stream through the fins.

9. A microwave oscillator comprising a hollow wave guide transmission line having a longitudinal axis of propagation, said hollow wave guide transmission line having wide and narrow cross sectional dimensions, means for directing an electron stream transversely across the interior of the hollow wave guide transmission line along an axis perpendicular to said axis of propagation, first and second apertures located in opposite wall portions of said hollow wave guide transmission line along a line parallel with the wide cross sectional dimension thereof for passage of said electron beam through said apertures, and slow wave propagating means positioned within the transmission line and extending transversely of the longitudinal axis of propagation of said transmission line and along the axis of the electron stream.

10. A microwave oscillator, comprising means for directing an electron stream along an axis, slow wave propagating means having a longitudinal axis positioned along the axis of the electron stream for passage of said stream through said propagating means, the slow wave

75

propagating means being substantially an integral number of half wavelengths long at the frequency of operation and having open circuited mismatched reflective terminations of substantially unity reflection coefficient at both ends whereby the slow wave propagating means is resonant at the operating frequency, and means along substantially the entire length of said slow wave propagating means for coupling of microwave energy therefrom for propagation in a direction perpendicular to the axis of the electron stream, said last-named means comprising a rectangular wave guide having its wide cross sectional dimension parallel with the axis of said electron stream.

11. A microwave oscillator comprising means for directing an electron stream along an axis, slow wave propagating means positioned along the axis of the electron stream, said last-named means including a pair of conductive members having spaced parallel surfaces on op-

5

posite sides of said axis and a plurality of inter-digital conductive fins projecting from said surfaces, the fins having openings therein aligned along the axis of the electron stream for passage of the stream through the inter-digital fins, and means for adjustable positioning at

least one of the members in a direction transverse said axis to vary the spacing between said parallel surfaces.
